WHEELED GUN-CARRIAGE.

1,166,839.

Specification of Letters Patent.

Patented Jan. 4, 1916.

Application filed June 9, 1915. Serial No. 33,113.

To all whom it may concern:

Be it known that I, NORBERT KOCH, residing at Essen-Rellinghausen, Germany, a citizen of the German Empire, have invented 5 a certain new and useful Improvement in Wheeled Gun-Carriages, of which the following is a specification.

The present invention relates to improvements in the gun-mount described in the application for Letters Patent, Serial Nr. 10 877186, filed December 14, 1914.

One embodiment of the invention is illustrated in the accompanying drawings for a gun carriage with a spread trail, and Figure 15 1 shows a side view partly in section of the parts concerned of the gun carriage; Fig. 2 is a top plan view of Fig. 1 partly in section; Fig. 3 is a top view of a detail in part section along line 3—3 of Fig. 1, and Figs. 20 4 to 6 are sections on lines 4—4, 5—5 and 6—6, respectively, of Fig. 2.

The axle tree A of the trail is provided with an annular enlargement A¹ (see Figs. 1, 2, 4 and 5), which has two diametrically 25 oppositely situated journal pins a² (Figs. 2 and 4). The axes of the journal pins a² run obliquely to the length direction of the trail. On the journal pins a² is mounted to oscillate a ring B, which is also provided with 30 two journal pins b¹, the common axis of which intersects at right angles the axis of the journal pins a². On the journal pins b¹ there is still another ring C mounted to oscillate, which serves as a bearing or socket 35 for a perpendicular hollow pivot D¹ of the top carriage D. In the top carriage D are carried the horizontal trunnions e¹ of the cradle E supporting the gun-barrel F (see Fig. 1). The top carriage D rests on a flange 40 c¹ (Figs. 1, 4 and 5) of the ring C, and is secured against lifting from the ring C by means of a nut d² threaded on the pivot D¹, and impinging against the edge of the ring C. Between the top carriage D and the 45 cradle E is inserted an elevating gear, while between the top carriage D and the ring C is provided a training gear, by means of which the top carriage can be trained around the axis of the pivot D¹. This training gear 50 is not shown in the drawing, as it may be constructed in any known manner. At its lower end, the pivot D¹ carries a spherical journal d³ (see Figs. 1 and 3) inclosed by a two-part ring G of corresponding shape. 55 The ring G is gripped by two other rings h¹

(see Fig. 1), which are secured on a rod H (see Figs. 1, 2, 3). This rod is secured in the ring G by means of screws h² (Fig. 3), which engage in a flange g¹ of the ring G, and in the upper one of the rings h¹. Between the rings h¹ is revolubly mounted still another ring h⁴ attached to a rod K on the ring G. The rods H and K are situated in the direction of the axes of the journal pins b¹ and a², respectively, and are provided 60 with internal threads permanently engaging with external threads on each of the rods L. The rods L are revolubly, but non-displaceably carried in sleeves M which are mounted to oscillate in forks N through the intermediary of journal studs n¹ (see particularly Fig. 6).

The forks N are revoluble in bearing brackets P by means of journals n², the axes of which are perpendicular to the common 70 axis of the journal studs n¹, these bearing brackets being attached to the trail sides O which are mounted to oscillate independent of each other around the axle tree A and are spread apart. On each trail side O is furthermore provided a bearing bracket R (Figs. 1 and 2) in which a shaft S carrying a hand wheel s¹ is revolubly, but non-displaceably mounted. Each of the shafts S is connected with the corresponding rod L 80 through a universal joint s².

If the gun carriage has been unlimbered on horizontal ground and the gearings L H and L K are in their middle position, the pivot D¹ will then be perpendicular. On 90 the other hand should the gun carriage be unlimbered on ground which is plane but inclined with regard to the muzzle horizon of the gun, the pivot D¹ may then be inclined both to the vertical plane running through the bore axis when the gun is in its middle position (inclined position of the wheels) and the pivot may also be inclined against the vertical plane running through the axis of revolution of the wheels T 100 ("hang-position" of the gun carriage), but it can only have an inclination to one of these two planes. In such a case the pivot D¹ will be placed perpendicularly before the firing, by turning one or both of the hand wheels s¹. As the rods L are non-displaceably mounted in the sleeve M, the rods H and K will experience an axial displacement upon the hand wheels s¹ being turned, which will cause an adjustment of the pivot D¹. 110

The adjustment of the pivot is carried out with the assistance of water-levels, or the like. If, on the other hand, the gun carriage is unlimbered on ground that is so constituted that the four supporting points of the gun carriage, namely the wheels and the two trail sides O, are not situated in one and the same plane, the following movement will occur. After one of the trail sides has reached the ground, the other trail side actuated by the preponderance of the trail ends of the gun carriage, will lower itself relative to the first trail side which already rests on the ground. As a consequence, the pivot D¹, not taking into account inclined carriage wheels and hang-position will be obliquely positioned through the intermediary of the rods L H or L K attached to that trail side which at the time is oscillating. The pivot D¹ will thereupon be turned out of this position into a perpendicular position through the turning of the hand-wheels s¹ before the firing takes place.

On unlimbering the gun carriage upon uneven ground and by adjusting the pivot by means of the hand wheels s¹, movement will occur in parts G d³, G h¹, M n¹, P n² and s².

The recoil shock appearing on firing will be transmitted in the device described above, through the top carriage D, the pivot and socket D¹ C, etc., to the rods H L S, K L S, and through the rods and their bearings to the trail sides O.

I claim:—

1. A wheeled gun carriage having a trail, a pivot member carrying the gun-barrel and enabling training thereof, means for oscil-

lating said pivot member around either of two intersecting axes, running at oblique angles relative to the axis of revolution of the carriage wheels, whereby said pivot may always be adjusted into vertical position irrespective of the condition of the ground, said means comprising systems of rods forming force-closing connections between said pivot and said trail.

2. In a wheeled gun carriage having spread-apart trail sides mounted to oscillate independently of each other on the wheel axle, a top carriage mounted in universal bearings on the wheel axle, said universal bearings having journals the axes of which intersect at right angles relatively to each other and at oblique angles relative to the axis of revolution of said trail sides, and means for oscillating the top carriage relatively to the trail sides, said means comprising a ball joint on the top carriage, two independent rings in said ball joint, one of said rings having threaded telescopic connection with one of the trail sides, and the other of said rings having similar connection with the other trail side, whereby said top carriage may be adjusted by said connections around one or the other of the intersecting axes of said journal pins, and the recoil shock transmitted through said connections to the trail sides.

The foregoing specification signed at Bar-
men, Germany, this 8th day of May, 1915.

NORBERT KOCH. [L.S.]

In presence of—

HELEN NUFER,
ALBERT NUFER.
